UNITED STATES PATENT OFFICE.

JOHN V. PILCHER AND JOHN F. BABBITT, OF LOUISVILLE, KENTUCKY; SAID BABBITT
ASSIGNOR TO SAID PILCHER.

SEPARABLE BUTTON.

Application filed May 24, 1924. Serial No. 715,637.

To all whom it may concern:

Be it known that we, JOHN V. PILCHER and JOHN F. BABBITT, citizens of the United States, and residents of Louisville, in the 5 county of Jefferson and State of Kentucky, have invented certain new and useful Improvements in Separable Buttons, of which the following is a specification.

Our present invention relates to improvements in separable buttons and is shown as 10 embodied in a button designed for link purposes, as for example, for use in cuffs, though not limited to this type of button.

The invention aims to provide a construction in which the parts will be capable of being readily fastened or snapped together and as easily separated, but which will be securely locked in their assembled condition and prevented from accidental displacement.

The invention further aims to do this in such a manner that the parts when assembled will have a broad bearing surface to prevent distortion under strains and also 25 in a manner which will enable the buttons to be economically manufactured and which will produce an extremely durable article.

With these and other objects in view, the invention comprises the novel features 30 of construction and arrangement and combination of parts hereinafter described, the precise nature and scope of the invention being ascertained and defined by the claims appended hereto.

In order that the invention may be more readily understood, we have annexed hereto drawings illustrative of the preferred embodiment thereof, in which drawings:—

Figure 1 is a transverse vertical section 40 through the assembled button;

Fig. 2 is a section on line 2—2 of Fig. 1;

Fig. 3 is a view of the upper or male section detached from the complementary section and with the push piece depressed to 45 retract the spring arms.

Fig. 4 is a detail plan view of the spring.

Fig. 5 is a view similar to Fig. 1, showing a modification.

Fig. 6 is a section on line 6—6 of Fig. 5 50 of the upper member detached.

Figs. 7 and 8 are similar views of a further modification, and

Figs. 9 and 10 are like views of a still further modification.

Referring by reference characters to these

drawings, and first to the form shown in Figs. 1 to 4, the numeral 1 designates what we term the "male" member of the button and 2 the "female" member. In the subjoined description, where we use the terms "upper" and "lower" in referring to the parts, it will be understood that this is for convenience and applies to the position shown in Figs. 1 to 3.

The male member 1 is of shell formation 65 comprising an upper portion or head 1^a which may be slightly dished, as shown, an intermediate portion 1^b providing a central shank portion with outwardly flared marginal portions, the upper of which is 70 interlocked by a joint of the folded seam type with the peripheral edge of the upper part or head. The outwardly flared lower part is joined by a similar seam to a plate or disc-like member 1^c which is provided 75 with a central protuberant part 1^d preferably semi-spherical shape. The lower or female member is similarly composed of a head 2^a and an intermediate or shank portion 2^b, and a disc-like member 2^c provided 80 with an open center, the edge 2^d of this open center being turned downwardly to form an annular shoulder. The protuberant part is of such size as to fit within the recess formed by the open center and hollow 85 shank and the relatively broad and flat bearing surfaces of the parts 1^c and 2^c afford wide bearing surfaces to support the button parts against rocking movement 90 when they are interlocked in a manner hereinafter described. To accomplish this interlocking we provide a spring 3 comprising a flat coil which is of such size as to be conveniently received between and held 95 clamped by the head portion 1^a and adjacent portion of the shank member. The ends of this spring are bent inwardly into parallelism, as indicated at 3^a, and adjacent the axes of the button are provided with depending spring arms having divergent portions indicated at 3^b, and outwardly or angularly turned ends 3^c which are seated in and adapted to project through 100 openings in the protuberant part 1^d, as shown in Figs. 1 and 3, the openings being 105 so located that when the spring arms are projected through the openings and the button parts are assembled, they will engage the annular shoulder 2^d and hold the parts firmly locked together. For manipu-

lating the spring arms I provide a push piece 4 of hollow formation and preferably tubular, which is of a size to be slidably guided by the contracted shank portion of 5 the male member of the button, this push piece extending through an opening in the top 1^a and being preferably covered by a cap 5 of inverted dish shape having an annular flange 5^a which engages beneath the 10 edge of the opening. The push piece 4 is provided with an opening 4^a for the passage of the parallel portions of the spring so as to enable the divergent arms to lie within the push piece, this opening 4^a being elongated 15 sufficiently to permit the free sliding movement of the push piece. The angularity of the portions 3^b of the spring arms is sufficient to cause their spring action to tend to hold the push piece in its elevated position, as shown in Fig. 1, and to return it to this position when the pressure of the thumb on the push piece is removed. To 20 assemble the button parts, as above described, the protuberant part 1^d is aligned 25 with the recess and the head 2^a and push cap 5 being grasped between a thumb and finger, pressure will cause the parts to be snapped together and firmly interlocked as soon as the pressure is relieved. To release 29 the parts, pressure on the cap 5 will withdraw the angularly bent spring ends from engagement with the flange 2^d, when the parts may be readily separated.

In the form shown in Figs. 5 and 6, instead of using tubular push piece we make 35 this in the form of a cylindrical member 4^d having a bifurcated or slotted lower end. The spring arms 3^d extend downward on diametrically opposite sides of the push piece 40 and are provided with inwardly converging or inclined portions 3^e underlying the top wall of the slot, the end portions of the arms being horizontally turned and extending in opposite directions through the openings in 45 the protuberant shell part and adapted to engage the flange of the shell part in the same manner as in the form first described. The tendency of the arms 3^d to spring towards each other causes their inclined portions to maintain the push piece elevated 50 and in the position shown in Fig. 5, but pressure on the push piece forces them apart and withdraws the ends of their horizontal portions from locking engagement with the flange of the female part.

In the form shown in Figs. 7 and 8 we 55 show a cylindrical push piece 4^f similar to the push piece of the first form, but make the spring arms of substantially elongated U form, as shown at 3^f, having inclined or diverging cam faces f' cooperating with the lower edges of the push member and having lateral projections f'' for effecting the locking engagement. In this form the inclination of the portions f' is such that it would

not or might not effect upward movement of the push member, and to insure this we provide a helical compression spring 6 between the top of the spring 4^f and the cap piece 5. Spring 3^f in this case is preferably made of 70 flat formation, as shown.

In the form shown in Figs. 9 and 10, which is similar to that just described, we provide the push member 4ⁱ with openings 75 to receive the inclined portions of the spring 3ⁱ, these openings being formed by slitting the sheet metal of which the push piece is made to form tongues i which are bent inwardly to form inclined cam members with which the inclined portions of the spring 80 arms coact in a manner which will be readily understood.

It will be obvious that various other modifications might be made without departing from the spirit of our invention. 85

Having thus described our invention, what we claim is:

1. A separable button comprising male and female members, said male member having a shell part to fit the recess of the female part, which is provided with lateral openings, a pair of spring arms carried by said male member having inclined portions and angular projections extending through said openings, said female member having retaining means for engaging said ends, and an axially movable push piece carried by said male member having opposed wall portions juxtaposed to said diverging spring arms. 100

2. A separable button comprising a recessed member and a complementary hollow member having a protuberant part to fit said recess, said hollow member having an enlarged head and relatively narrow shank, a spring comprising a coil located in said enlarged head and having diverging arms located in said shank and having angularly turned ends projecting through openings in said protuberant part, said recessed member having retaining means to engage said spring ends, and a push piece slidably guided in said narrow shank and coacting with said diverging spring arms. 110

3. A separable button comprising a female member having a relatively broad flat face with a centrally disposed recess, there being an annular flange surrounding said recess forming a shoulder, and a male member having a relatively broad flat face to coact with said flat face of the female member and having a protuberant part having openings in its wall adjacent said shoulder, spring arms having angularly turned ends extending through said openings and engaging said shoulder, and means for contracting said arms to disengage said ends from said shoulder. 120

4. A separable button comprising a recessed member and a complementary hollow 130

member having a protuberant part to fit said recess, said hollow member having an enlarged head and relatively narrow shank, a spring comprising a coil located in said enlarged head and having diverging arms located in said shank and having angularly turned ends projecting through openings in said protuberant part, said recessed member having retaining means to engage said spring ends, a hollow push piece slidably guided in said narrow shank and embracing said diverging arms, said hollow push piece having elongated openings through which the spring extends.

5. A separable button comprising a recessed member and a complementary hollow member having a protuberant part to fit said recess, said hollow member having an enlarged head and relatively narrow shank, a spring comprising a coil located in said enlarged head and having diverging arms located in said shank and having angularly turned ends projecting through openings in said protuberant part, said recessed member having retaining means to engage said spring ends, a hollow push piece slidably guided in said narrow shank and embracing said diverging arms, said hollow push piece having elongated openings through which the spring extends, said push piece extending through an opening in the outer wall of said complementary hollow member, and a push cap covering the end of said push piece and extending through the opening and having a part extending from its periphery and underlying the edge of the opening in said outer wall.

6. A separable button comprising a hollow member having an enlarged head and base and contracted shank, and a protuberant part carried by said base, a hollow push piece slidably guided in said shank and with means whereby it may be manipulated from the head of said hollow member, said push piece having an opening in its walls, a coil spring located in said enlarged head and having portions projecting through said opening and bent downwardly to form diverging arms with angularly turned ends located below the lower end of said push piece, and a complementary member having a recess to receive said protuberant part and an annular shoulder to engage said angularly turned ends of the diverging arms.

7. A separable button comprising male

and female parts, said female part comprising a shell having an outwardly flared upper end, and a disc having an open center with an angularly turned edge forming an annular shoulder, and an outer edge interlocked with said flared end, and a male part comprising a shell having a shank with a flared lower edge and a disc-like member having its edge interlocked with said flared lower edge and having a central protuberant part of substantially semi-spherical shape to engage said open center, and spring catches projecting through openings in said protuberant part and adapted to engage said flange and means for operating said catches.

8. A separable button comprising complementary parts, the one having an opening and the other a protuberant part to enter said opening, said members having relatively wide flat contacting faces surrounding said opening and protuberant part respectively, spring locking means carried by one of said parts for engaging the other part to hold the parts locked together, and a push piece for actuating said spring locking means.

9. A separable button comprising complementary parts, the one having an opening and the other a protuberant part to enter said opening, said members having relatively wide flat contacting faces surrounding said opening and protuberant part respectively, spring locking means carried by one of said parts for engaging the other part to hold the parts locked together, and an axially movable push piece for actuating said spring locking means.

10. A separable button of the link type comprising male and female parts, each comprising a sheet metal body having outwardly turned ends, a sheet metal head and base plate having edges overturned to engage said ends, said base plates being relatively broad and affording wide coating surfaces to prevent rocking of the parts when juxtaposed, resilient locking means carried by one of said parts for engaging the other part, and a push piece for actuating said spring locking means.

In testimony whereof, we affix our signatures.

JOHN V. PILCHER.
JOHN F. BABBITT.
